Application April 28, 1941, Serial No. 100,657

Term of patent 14 years

To all whom it may concern:

Be it known that I, Vera C. Hodges, a citizen of the United States, residing in Los Angeles, in the county of Los Angeles and State of California, have invented a new, original, and ornamental Design for a Mounting Bracket for an Aircraft Generator, of which the following is a specification, reference being had to the accompanying drawing, forming part thereof.

Fig. 1 is a perspective view of a mounting bracket for an aircraft generator, showing my new design.

Fig. 2 is a plan view of the device shown in Fig. 1.

Figure 3 is a side elevational view of said device, and

Figure 4 is an elevational view, on a slightly reduced scale, showing the opposite side to that illustrated in Figure 3.

I claim:

The ornamental design for a mounting bracket for an aircraft generator, substantially as shown.

VERA C. HODGES.
